UNITED STATES PATENT OFFICE.

WILFRED I. OHMER AND DAVID B. WHISTLER, OF DAYTON, OHIO, ASSIGNEES TO THE RECORDING AND COMPUTING MACHINES COMPANY, OF DAYTON, OHIO, A CORPORATION OF OHIO.

FARE-RECORDING MECHANISM.

1,229,646.

Specification of Letters Patent. Patented June 12, 1917.

Application filed August 31, 1912. Serial No. 718,001.

To all whom it may concern:

Be it known that we, WILFRED I. OHMER and DAVID B. WHISTLER, citizens of the United States, residing at Dayton, in the county of Montgomery and State of Ohio, have invented certain new and useful Improvements in Fare-Recording Mechanism, of which the following is a specification, reference being had therein to the accompanying drawing.

This invention relates to fare recording mechanisms and the object of the invention is to provide a mechanism which will receive, indicate, count, register and make a classified record of the fares received. A further object of the invention is to provide such a mechanism of a construction which will permit the several parts thereof to be located in the most desirable positions and in which the several parts may all be operated by a single act on the part of the conductor or other operator. It is also an object of the invention to mount the several parts of the mechanism upon a single frame, the construction and arrangement being such that each part will be supported in the desired position and will also be operatively connected with a single operating device. Further, it is an object of the invention to so construct and mount the frame that the structure as a whole may readily be moved from one position to another, this being particularly desirable in devices used in connection with those cars having the entrance midway between the ends thereof.

In the accompanying drawings, Figure 1 is a front elevation of the mechanism showing it as it appears to a passenger entering the car; Fig. 2 is a side elevation of the same; Fig. 3 is a side elevation of the fare box showing the operating mechanism therefor; Fig. 4 is a transverse sectional view, taken on the line $z-z$ of Fig. 2 showing the foot operating device; Fig. 5 is a top, plan view of the mechanism with the indicator removed; Fig. 6 is a detail view of the operating mechanism for the fare box; Fig. 7 is a plan view of a portion of this mechanism showing the connection with the operating rod; Fig. 8 is a detail of the pawl and ratchet forming a part of the operating mechanism for the fare box; Fig. 9 is a detail view of a part of the counting mechanism for the fare box; Fig. 10 is a front elevation of the mechanism partially broken away, of a fare box such as is embodied in the present mechanism; Fig. 11 is a vertical sectional view taken on the line $x-x$ of Fig. 10 looking in the direction of the arrows; and Fig. 12 is a sectional view taken on the line $y-y$ of Fig. 11 looking in the direction of the arrows.

In these drawings we have illustrated one embodiment of our invention and have shown the entire mechanism mounted upon a single frame or pedestal which is provided with a single operating mechanism operatively connected with each part to be operated to enable a single act upon the part of the conductor to actuate each of the operable parts of the mechanism as a whole. Further, we have shown this frame or pedestal so constructed and mounted that it can be moved into different positions without disturbing the relative positions of the parts. This latter feature is especially desirable where the device is used in connection with cars having entrances at both sides which are alternately used and it is desirable that the machine should face first toward one side of the car, and then toward the other side. In that form of the device here illustrated and which is designed particularly for use in connection with a fare register for street cars, the frame is shown as comprising two parts, a lower portion or pedestal proper comprising upright members 1 connected at their lower ends by transverse members 2 and at their upper ends by a transverse member 3, this latter being preferably in the form of a plate to form a supporting table on which is mounted a fare box 4. Rigidly mounted within the rectangular frame or pedestal 1 is a fare recorder having a casing 5. Mounted on the base portion of the frame or pedestal, at one side of the support for the fare box, are two upwardly extending standards 6, which are shown as hollow rods, on the upper ends of which is supported an indicator 7. This arrangement of the frame enables the fare box 4 to be supported in the position in which it will be readily accessible to the passenger as he enters the car. The fare box which includes a suitable casing may be of any suitable construction, that here shown being a well known commercial machine and, aside from its operating devices, forming no part of the invention.

In order that the operation of the fare box may be understood it will be briefly described. At the upper portion of the box or casing 4 is a hopper or coin receiver 8, the bottom of which is provided with a plurality of holes 9 to permit the passage of coins which may be dropped into the hopper. The size of these holes is such that they will not permit the passage of any coins which are larger than the counting mechanism hereinafter to be described is adapted to handle. In the present instance the holes are of a size to permit the passage of a five cent piece, thus enabling one cent pieces, five cent pieces and ten cent pieces to be inserted in the fare box. Leading down from the hopper 8 is a tortuous channel 10 having its lower end closed by a swinging door 11. This passageway terminates within a reduced upper portion 12 of the fare box having at its lower end swinging doors 13 upon which the coins drop from the passageway 10. The walls of this upper portion of the fare box are preferably of glass to permit the coins deposited within the same to be inspected both by the conductor and passenger. These doors are provided with levers 14, one of which is connected by a pin 15 with a slotted arm 16 which, in turn, is adapted to be rocked about its axis to open and close the doors, this rocking movement being imparted to the arm in a manner to be hereinafter described. Mounted within the lower portion of the fare box is a revoluble disk 17 adapted to pick up the coins which are dropped into this portion of the fare box through the doors 13 and through mechanism, which will be hereinafter described, actuate counting devices 18 to add thereto a number of units equal to the denomination of the coin. Rotation is ordinarily imparted to this disk by means of a shaft 19 journaled in the side of the fare box and connected with the disk by means of suitable gearing. In the ordinary use of the fare box as now built rotatory movement is imparted to the shaft 19 and disk 17 by means of a handle 20. In the present mechanism movement is preferably imparted to the shaft 19 by the operating device for the mechanism as a whole and to this end the shaft 19 has rigidly secured thereto a ratchet wheel 21. Gears 22 and 23 are loosely mounted on the shaft 19 on opposite sides of the ratchet wheel 21. Rigidly secured to each gear is an arm 24 carrying a pawl 25 adapted to engage the ratchet wheel when moved in a forward direction. The gears 22 and 23 mesh, respectively, with toothed segments 26 and 27 journaled on a stud 28 mounted on the side of the fare box. These segments are connected by means of links 29 with the respective ends of crank arm 30 pivotally mounted between its ends on a stud 31 projecting from the side of the fare box. It will be

apparent, therefore, that when rocking movement is imparted to the lever 30 the segments will be moved in opposite directions. When the lever is moved in one direction the segment 27 will rotate the gear 23 in a direction to cause its pawl to engage the ratchet wheel, while the pawl of the gear 22 will ride over the ratchet. When the movement of the lever is reversed the pawl of the gear 23 will ride over the ratchet while the pawl of the gear 22 will operatively engage the ratchet. In this manner the shaft is rotated continuously in the same direction by the opposite movements of the rocking lever. The rocking movement may be imparted to the crank arms 30 in any suitable manner. In the present instance a lever 32 is pivoted upon the side of the fare box and has at one end a pin, as indicated at 33, to engage a slot in the adjacent end of an arm 34. The opposite end of the lever 32 is connected with the operating device for the mechanism as a whole which in the present instance comprises a vertical reciprocating rod 35 which is here shown as extending upwardly through one of the hollow standards 6 and connected at its lower end with an arm 36 secured to a shaft 37 journaled in bearings near the bottom of the frame 1 and also having rigidly secured thereto a foot lever 38 by means of which the conductor or other operator will rock the shaft 37 and thus impart vertical reciprocatory movement to the operating rod 35, which movement is transmitted through the mechanism just described to the shaft 19 to rotate the latter continuously in one direction. The slotted arm 16 for operating the doors 13 at the bottom of the upper portion 12 of the fare box is rigidly connected with the lever 30 on the stud 31 and consequently will be rocked about the axis of that stud upon each operation of the foot lever, thereby opening and closing the doors 13.

Fare boxes of various constructions can be utilized in connection with the invention. That here used for the purpose of illustrating the invention comprises, as stated, the disk 17 mounted on an inclined axis and adapted to pick up the coins which are dropped into the fare box. This disk is rotated by means of the handle 20 on the shaft 19 through gears 90 and 91, the latter being connected with the shaft which carries the disk. The inclined disk 17 is provided on its upper face with a series of pockets, each of which is adapted to receive and lift a coin of a single denomination only. These pockets are shown as formed in the present instance by means of lugs 125, the lugs of the different pockets being spaced different distances apart. When the disk is rotated by means of the handle 20 or otherwise, the pockets, which are arranged near the periphery of the disk, pass through the lower

part of the hopper and pick up single coins and carry these coins upward to the highest point of the disk, near which is arranged a device controlled by the coins for causing the operation of a registering device 18. The operation of this counting device is brought about by means of a disk 126 rigidly secured to and rotating with the coin lifting disk 17, and having on its periphery 10 a plurality of toothed racks, each rack comprising one or more teeth. The number of racks corresponds with the number of pockets on the face of the disk and each rack contains a number of teeth corresponding 15 to the denomination of the coin which its particular pocket is adapted to lift. Mounted in the rear of the two disks and on an axis arranged at approximately right angles to the planes of the disks is a pinion 20 127 which is carried by a shaft 128 slidably mounted in its bearings and adapted to be moved axially to carry the pinion 127 into and out of the path of the teeth on the edge of the disk 126. To accomplish this movement a lever 129 is pivotally mounted on the frame of the machine, connected between its ends with the shaft 128, and has its free end arranged in the path of a finger 130 which is pivotally mounted on a rock shaft 25 131 journaled on the frame of the machine and extending in front of the coin lifting disk 17. Rigidly secured to the shaft 131 and extending above the disk 17 is a rock arm 132 having at its free end a roller 133 30 adapted to travel over the face of the disk in the path of the pockets 125. A spring 134 holds this roller normally in engagement with the face of the disk. The several racks on the edge of the disk 126 are so arranged 35 with relation to their respective pockets that when a coin in one of these pockets engages the roller 133 and actuates the rock arm 132 and shaft 131, the pinion 127 will be moved in front of and into the path of the particular rack corresponding to the pocket containing the coin with which the roller 133 is in engagement. Consequently, the pinion 127 will be rotated a distance corresponding to the denomination of that particular coin. This movement is transmitted 40 to the counter 18 by means of suitable gearing comprising a gear 135 in the hub of which the shaft 128 is slidably mounted, but which is connected thereto in such a manner 45 as to cause the gear to rotate with the shaft. The movement is transmitted from the gear 135 through gears 136, the shaft 96 and gears 137 to the actuating shaft 95 for the counter, on which is the actuating gear 94. 50 It will be obvious, therefore, that the operation of the fare box causes coins to be lifted from the hopper and registered according to their value. After the coin has passed the roller 133 it is discharged into a coin 55 chute 139 which conveys it to the coin box.

Thus the coins are accessible only after they have been registered.

A recording device for preserving a classified record of the various fares received is preferably mounted in the frame or pedestal 70 1 below the fare box. In this position it is readily accessible for the printing and resetting operations and does not occupy any additional space. In the present mechanism we have embodied a fare recorder of a well known type which in all its essential characteristics is shown and described in the patent issued to Ohmer, Whistler and McAllister, No. 990,666. This mechanism forms no part of the present invention and only so 75 much of the same will be described as is necessary to a clear understanding of the operation of the mechanism as a whole. The recording devices proper comprise a plurality of groups of counter wheels 39 loosely 80 mounted on a resetting shaft 40. The units counter wheel of each group is provided with an actuating gear, which is not here shown, and suitable transfer devices are provided for transferring the count from the 85 units wheel to the tens wheel, etc. By rotating the shaft 40 the several counter wheels of each group will be picked up and returned to their zero positions. These counter wheels are preferably printing 90 counter wheels or type wheels and suitable mechanism is provided for printing a record, but this mechanism is not here shown. A single actuating device is provided for the several groups of fare counters and preferably comprises an actuator gear 41 slidably mounted on a shaft 42, but so connected to said shaft that it will rotate therewith. Longitudinal movement is imparted to the gear along the actuator shaft 42 by means of 95 a yoke 43 carried by a nut 44 mounted on a screw-shaft 45 which constitutes the setting shaft and projects beyond the end of the frame in which the mechanism is mounted. Motion may be imparted to the screw-shaft 45 to set the actuator in a position to 100 actuate the desired group of counters by any suitable mechanism. In the present instance the vertically reciprocating operating rod 35 is so mounted that it is also capable 105 of a rotatory movement and to this end it is provided with a swiveled connection 46 at a point above its point of connection with the arm 36. Mounted on the shaft is a handle 47 which is connected thereto in such a manner as to cause the shaft to rotate therewith but to permit the shaft to have vertical movement relatively thereto. This handle projects through a slotted casing 48 which is provided with suitable stops marked to indicate the several fares which the mechanism is designed to record. As here shown the shaft 35 has a crank arm 49 connected by means of a link 50 with a crank arm 51 carried by a stud 52 and connected with a seg- 110 115 120 125 130

mental gear 53. The segmental gear 53 meshes with a small gear 55 carried by a stud 56 on which is mounted a larger gear 57. This latter gear meshes with a pinion 58 on 5 the setting shaft 45. The ratio of the gearing is such that the movement of the handle 47 into engagement with any one of the stops on the slotted casing 48 will rotate the setting shaft a distance sufficient to cause 10 the actuator 43 to assume operative relation to that group of fare counters corresponding to the indication on the casing 48 adjacent to which the handle has been stopped. The fare is then added to this particular 15 group of counters by rotating the shaft 42 and actuator gear 41. This movement of the shaft 42 is accomplished in the manner shown and described in the patent to which we have above referred. It is unnecessary 20 to describe the details of this mechanism but it is sufficient to note that the operating mechanism comprises a reciprocating bar 59 which is operatively connected with the shaft 42. Reciprocatory movement is im- 25 parted to the slide bar 59, Figs. 2 and 5, by the reciprocation of the operating rod 35 and to this end a lever 60 is pivotally mounted between its ends on the frame of the recorder and has one end connected to the 30 slide bar and the other end connected with the operating rod 35. Obviously, therefore, the reciprocation of the rod 35 will impart reciprocatory movement to the slide bar 59 and will thus cause the fare to be recorded. 35 Not only does this recorder make a record of the fares collected on each trip and the total amount of cash collected on each trip but it makes a record of the total amount of each item for several trips, these totalizing 40 counters being shown at 84 and being actuated by the same actuator which actuates the trip counters.

The recorder is provided with printing devices for taking a record from the counter 45 wheels, which are provided with type. This printing mechanism may be of any suitable character but that employed in the device of the patent to which we have above referred comprises a platen 82 mounted in a carriage 83 slidably mounted on the frame 50 of the machine and adapted to be reciprocated therein to cause the platen to move across the type wheels and thus press the paper, or other material on which the record 55 is to be impressed, against the type.

The indicator 7, which is mounted upon the hollow standards 6 of the frame, preferably comprises two parts, first, an indicator to indicate the class of the fare which 60 has been recorded and, second, a counting indicator to count each fare and indicate the total number of fares for the trip. These indicators are mounted in a casing having sight openings 61 and 62, arranged 65 one above the other, through which the in-

dicators are visible. Preferably, both sides of the casing are provided with sight openings and the indicators are of such a character that they are visible from both sides thereof, thus enabling the indication to be 70 read by the passenger who is entering the car and also by those within the car. The indicator to indicate the class of the fare received preferably comprises a series of blades 63 each having printed on both sides 75 thereof the name of one class of fare. Normally these blades are supported below the sight opening and are moved upward one at a time to enable the indication on this one blade to be read. This may be accomplished in any suitable manner but preferably each blade is connected to the end of the casing or other fixed part of the mechanism by means of links 64 which are so shaped as to not interfere one with the other in the movements of the several blades. Suitable selective mechanism is provided 80 for actuating the desired blade and is adapted to be actuated by the vertically reciprocating actuating rod 35. A very simple device for this purpose consists in a projection or pin 65 secured to the upper portion of the rod 35 and so placed that when the handle 47 has been moved into engagement with any one of the stops on the casing 48 the pin 65 will be in alignment 85 with the link of one of the indicator blades 63 and the upward movement of the operating rod 35 will move this particular blade into alignment with the sight opening. Suitable means may be provided for retaining the blade in this position until another blade has been actuated but this means 90 forms no part of the present invention and is fully shown and described in Patent No. 1,132,234, granted to Whistler and Ripsch 95 March 16th, 1915, in which this entire indicating mechanism is shown and described. The counting indicator preferably 100 comprises a series of indicator wheels 66 arranged in the manner shown and described in the above mentioned application to enable the count to be read from both sides of the indicator casing. These indicator wheels 105 constitute a trip register and are actuated to add one to the count upon each 110 operation of the operating rod 35 and, to this end, are provided with ratchet wheels 74 and a pawl frame or yoke 75 to which are secured pawls 76. The yoke 75 has a 115 slotted arm 77 which receives a pin 78 carried by an arm 79 rigidly secured to the 120 shaft 35, thus causing the yoke 75 and the pawl carried thereby to operate upon each 125 operation of the reciprocating rod 35. The indicator wheels 66 are reset at the end of each trip and to this end are preferably connected with the resetting shaft 40 so as to be controlled in unison with the recording counters 39. To this end the shaft 130

67 on which the indicator wheels 66 are mounted has a bevel gear 68 meshing with a bevel gear 69 on a shaft 70 extending downward through one of the hollow stand-
ards 6 and connected by bevel gearing 71 with a shaft 72 which is also connected by bevel gearing 73 with the resetting shaft 40. Consequently, when the resetting shaft is rotated to reset the counters to zero, which
10 is done by hand in the manner described in the above-mentioned patent, the counting indicator wheels 66 will also be reset to zero.

This device is particularly adapted for use upon street cars and the like where the passengers enter first from one side of the car and then, on the opposite trip, from the other side. It is, therefore, desirable that the mechanism should be of such a character that it can be moved into different positions to enable the fare box to be brought into a position readily accessible to the passengers as they enter the car and to support the indicating mechanism in a position where it will be visible both to the passenger who enters the car and to the passengers within the car. To this end the pedestal or supporting frame is movably mounted upon the floor of the car or other supporting structure. While the character of this movable mounting may be varied as circumstances may dictate it is here shown as a pivotal connection and consists merely of a bolt so secured in the floor of the car, extending through the lower transverse member of the pedestal and provided with a hand nut 81 for clamping the frame or pedestal in its adjusted position.

It will be noted that the recording mechanism comprises essentially a receptacle to receive and display the fare paid and having operable devices to control the passage of the fare, in combination with a recording device to make a record of a fare, the operable parts of the receptacle and the recording device being so connected that the recorder must be operated every time the operable parts of the receptacle are operated to permit the fare to pass. The fare is not touched by the conductor until after a record has been made. It is, therefore, necessary that he should record the fare received. This is necessary for two reasons. First, the fare is exposed to the view of all persons in the vicinity as well as to the conductor and the passenger who paid the fare. Likewise, the indicator which indicates the class of fare which is recorded is exposed to the view of these parties. Under these circumstances the risk of recording a fare other than that received is great. Again, the record which is turned in at the office must correspond with the actual collections. Otherwise, there is a garbled record and explanation must be made. It will be apparent, therefore, that by
65 combining these parts we not only collect the

fares without the same passing through the hands of the conductor and make a record of the fares but we impose upon the conductor the necessity of correctly recording every fare received. The possibility of manipulating the record to his own advantage is practically eliminated. It will be noted that the entire mechanism is mounted upon the pedestal, thus providing a unitary structure which can be moved from one place to another without altering the relative positions of the several parts of the mechanism; further, it will be apparent that a single operation of the foot lever, or other operating device, will cause the operation of the trap doors 18 to deposit a fare in the main body portion of the fare box, will actuate the cash counting devices for the fare box, will indicate the class of the fare received, will count and indicate the number of fares received on that trip, and will make a classified record of the fares received. Further, it will be noted that the mechanism is very compact in arrangement and simple in its construction. In this connection it may be noted that while the recording device and indicators take care of both the paper fares and cash fares the fare box receives and counts only the cash.

While we have shown and described one embodiment of our invention it will be understood that this has been chosen for the purposes of illustration only and that we do not desire to be limited to the details of construction shown and described, for obvious modifications will occur to a person skilled in the art.

Having thus fully described our invention what we claim as new and desire to secure by Letters Patent, is:

1. In a fare recording mechanism, a fare-box having operable parts, a recorder, an indicator to show the kind of fare received, an indicator having counters to count the fares of all kinds received, a setting device for said recorder, a separate setting device for said first-mentioned indicator, means common to said setting devices for setting the same to record and indicate a specified fare, and means common to said operable parts, recorder and indicators for actuating the same after the setting devices have been adjusted.

2. In a fare recording mechanism, a recorder provided with a setting device, an indicator to show the kind of fare received and provided with a setting device, an indicator having counters to count the fares of all kinds received, and a single operating mechanism common to said recorder and indicators and operable in a plurality of directions, whereby the movement of the operating mechanism in one direction will set said recorder and one of said indicators and movement of said operating mechanism in

another direction will actuate said recorder and indicators after the adjustment of the setting devices.

3. In a fare recording mechanism, a recorder, a fare box, and a plurality of indicators arranged in alinement, and a reciprocating rod connected to the same to simultaneously actuate the recorder, fare box and indicators by one operation.

10 4. In a fare recording mechanism, a fare box, a fare recorder provided with means for making a classified record of each fare received, an indicator having selective mechanism to cause the same to indicate the 15 class of each fare received; an operating rod, means for imparting reciprocating and rotary movement to said rod, connections between said rod and said recorder and between said rod and said indicating mechanism, whereby the rotation of said rod will set said recorder and said indicating mechanism, and connections between said fare box, said recorder and said indicator, whereby the reciprocation of said rod will actuate 20 said parts.

5. In a fare recording mechanism, a fare box, a recorder, an indicator to show the kind of fare received, a setting device for said recorder, a setting device for said indicator, means common to said devices for operating the same to set the recorder and indicator to record and indicate a specified fare, and means common to said fare box, recorder and indicator for actuating the 35 same after the setting devices have been adjusted.

6. In a fare recording mechanism, an indicator adapted to count the fares of all kinds received, a fare box, automatic register actuating devices in said fare box, a counter to which said devices are operatively connected, a fare recorder provided with counters to register the fares of various kinds and under the control of the operator, 45 whereby the counter of said fare box acts as a check upon the counters of said recorder, and an actuating device common to said indicator, fare box and recorder to cause the actuation of the same.

50 7. The combination, with a fare box having automatic coin-controlled operating mechanism therein and a register controlled thereby, of a fare recorder to make a separate record of the fares registered by said fare box, means to manually set said fare recorder to enable it to record fares of various denominations, and operating mechanism common to said fare box and said recorder, said operating mechanism comprising a single actuating device separate

from said means to manually set said fare recorder, whereby said fare box mechanism will automatically register its coin of whatever denomination and the recorder will register a coin of the denomination for which it is set

65 8. The combination, with a counter having automatic devices beyond the control of the conductor for actuating the same to register coins of various denominations thereon, of a second counter having setting means, and means to cause the actuation of said automatic devices and said second counter, whereby said counters serve to check each other.

70 9. In a fare recording mechanism, a fare box, having automatic registering mechanism beyond the control of the conductor, a fare recorder under the control of the conductor and provided with means to manually set the same to record a specified fare, and means common to said fare box and recorder for actuating the same after the recorder has been set.

75 10. In a fare recording mechanism, a fare box having automatic registering mechanism beyond the control of the conductor, a recorder provided with registering mechanism, whereby the mechanism of the fare box and recorder serve to check each other 90 to insure accuracy, a fare indicator to indicate the different classes of fares, and means which manually set said fare recorder and said indicator to cause them, respectively, to record and indicate fares of various denominations, and means common to said fare box, recorder and indicator for actuating the same after the recorder and indicator have been set.

80 11. In a fare recording mechanism, a fare box provided with registering mechanism which is automatic and beyond the control of the conductor, a recorder provided with counters, a setting device and printing mechanism, means for setting said recorder to record a specified fare, and means common to said fare box registering mechanism and said recorder for actuating the same after the recorder has been set, whereby the records of the fare box and recorder serve to 95 check each other, one being under the control of the conductor and the other beyond his control.

100 In testimony whereof, we affix our signatures in presence of two witnesses.
